UNITED STATES PATENT OFFICE.

WILLARD P. WINGATE, OF WAXHAW, NORTH CAROLINA.

YARN-GUARD FOR REELS.

No. 798,939.

Specification of Letters Patent.

Patented Sept. 5, 1905.

Application filed November 14, 1904. Serial No. 232,704.

To all whom it may concern:

Be it known that I, WILLARD P. WINGATE, a citizen of the United States, residing at Waxhaw, in the county of Union and State of 5 North Carolina, have invented a new and useful Yarn-Guard for Reels, of which the following is a specification.

This invention relates to yarn and cotton reels or swifts, and has for its principal object to provide novel means for preventing the soiling of the yarn as the hanks are removed through the doffing-wheel.

A further object of the invention is to provide a novel form of bearing or oil-cup for 15 the reception of the doff-wheel end of the reel-shaft.

With these and other objects in view, as will more fully hereinafter appear, the invention consists in certain novel features of construction and arrangement of parts herein-after fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is 30 a perspective view of a portion of the reel provided with a yarn-guard constructed in accordance with the invention. Fig. 2 is a similar view of the doff-wheel and its bearing detached. Fig. 3 is a sectional elevation of the 35 doff-wheel and bearing. Fig. 4 is a transverse sectional elevation of the device on the line 4-4 of Fig. 3.

Similar numerals of reference are employed to indicate corresponding parts throughout 40 the several figures of the drawings.

In reel doff-wheels of ordinary construction much difficulty is experienced in the removal of the yarn after the winding operation, it being practically impossible with reels in use at 45 the present time to prevent soiling of the yarn by the lubricating material necessarily employed for the bearings of the reel-shaft.

In the drawings there is shown a portion of the frame 10 of a reel 11, the latter being 50 of the usual construction. One end of the reel-shaft 12 is supported in a doff-wheel 13, that is provided with the usual gap and has a peripheral groove receiving a curved support-

ing-bracket 14, on which it turns to facilitate the removal of the skeins of yarn. 55

The hub of the doff-wheel is extended in the direction of the reel to form an elongated sleeve 16, that receives the end of the reel-shaft 12, and on the opposite side of the doff-wheel is a peripherally-threaded hub portion 60 17, that receives a screw-cap 18 in order to conceal and guard the end of the reel-shaft. To the shaft 12 is secured a ring or collar 18', that turns against the inner surface or bore of the sleeve 16 and prevents the passage of 65 oil in the direction of the reel, and said sleeve is extended beyond the collar 18' to the hub of the spider at the end of the reel or swift.

In the hub of the doffer is formed an opening through which oil may be introduced for 70 lubricating purposes, and said opening is threaded for the reception of a screw 20, which when in position does not extend beyond the periphery of the hub, so that it will not interfere with the ready removal of the 75 yarn.

When the device is in use, the elongated sleeve and the cap will prevent the passage of the oil, so that the skeins of yarn may be 80 allowed to come into contact with the hub and doff-wheel without danger of being soiled. The device is further advantageous in that it permits the yarn being removed more quickly than with reels of the present construction, where great care must be exercised in the 85 handling of the skeins in order to prevent their coming into contact with the shaft.

Having thus described the invention, what is claimed is--

1. In a reel or swift, a doffing-wheel having 90 a hub portion arranged for the reception of the reel-shaft, said hub being inwardly extended to engage against the end of the reel, means for preventing the flow of lubricating material forward through the extended hub 95 portion to the reel, and a cap carried by the hub and serving to conceal the end of the shaft.

2. In a reel or swift, a doffing-wheel having an extended hub or sleeve forming a bearing, a reel-shaft carried by said hub or sleeve, a 100 collar rigidly secured to the shaft and bearing against the inner face or bore of the sleeve, and a cap for concealing the end of the reel-shaft.

3. In a reel or swift, a doffing-wheel in which 105 the hub at one side is extended to form an elongated

gated sleeve, and on the opposite side is provided with peripheral screw-threads, a reel-shaft extending through the hub, a rigid collar on the reel-shaft bearing against the inner 5 face of the extended hub, said hub being extended inward for contact with the end of the reel, and a hollow cap-piece carried by the threaded portion of the hub.

In testimony that I claim the foregoing as my own I have hereto affixed my signature in 10 the presence of two witnesses.

WILLARD P. WINGATE.
